UNITED STATES PATENT OFFICE.

CHARLES J. KINTNER, OF NEW YORK, N. Y.

SAFETY APPLIANCE FOR RAILWAYS.

No. 829,969.

Specification of Letters Patent.

Patented Sept. 4, 1906.

Application filed January 27, 1905. Renewed May 9, 1906. Serial No. 315,854.

To all whom it may concern:

Be it known that I, CHARLES J. KINTNER, a citizen of the United States, residing in New York, borough of Manhattan, county 5 and State of New York, have made a new and useful Invention in Safety Appliances for Railways, of which the following is a specification.

My invention is directed particularly to improvements upon safety appliances for railways disclosed in prior applications for patents filed by me in the United States Patent Office and especially to a system embodied in United States application bearing Serial No. 15 211,342, filed June 6, 1904; and it has for its objects, first, to provide improved arrangements of track-circuit-controlling conductors whereby better insulation is effected for such parts, and I am enabled to use signal and 20 switch controlling batteries of higher voltage than is possible with existing types of railway safety appliances which rely upon track-circuit-closing devices controlled by the wheels and axles of a car as it passes over the 25 route; second, to provide a system of electrically-controlled railway-signals embodying home and distant signals, in which the two sets of signals are absolutely independently controlled—that is to say, the distant 30 signal is not in any sense acted upon or controlled by its companion home signal, thereby avoiding any possibility of an error due to the failure of the home signal where the distant signal is made dependent upon the positive 35 operation or action of the former; third, to provide an improved system of track-circuit-closing rails or conductors like that disclosed in my before-mentioned application, in which said track-circuit closing or controlling 40 rails offer a minimum mechanical resistance to the flanges of the wheels of the cars and a minimum amount of metal is required therefor; fourth, to provide a system of sectional track-circuit closing or controlling 45 rails or conductors which are yieldingly sustained by springs closely adjacent to either or both track-rails; fifth, to provide a system of sectional track-circuit closing or controlling rails or conductors which are effectually insulated from the weather at all times and in 50 such manner that even though a section of the track be flooded a car in passing thereover will control and operate the signals or the circuit connections affected by such track-circuit closing or controlling rails without a 55 possibility of failure, thereby making the sys-

tem practical for all conditions of weather; sixth, to combine with such track-circuit closing or controlling rails a system of electrical conductors for controlling the movements of 60 trains, both as to signals and as to the power-current, which conductors are effectually insulated within a conduit or conduits closely adjacent to either one or both of the track-rails; seventh, to control the movements of 65 semaphores through the agency of electric motors having circuit connections such that the motors are always cut out of circuit when the semaphores are at "safety," they being always positively geared to the armatures of 70 the motors in such manner that when released the armatures of the motors and interconnecting gearing act as retarding means to prevent the too sudden movement of the semaphores in such manner as to harm them 75 by impact or otherwise with parts of the signal-sustaining posts; eighth, to provide a novel arrangement of home and distant semaphores such that the home semaphore always gives indication of "danger" by 80 hanging in a definite position, preferably vertically, and the distant-semaphore indication of "caution" by hanging in a different position, preferably transverse the track, the arrangement being such that when 85 both semaphores are set they are displayed at right angles to each other, while when both are at "safety" they are wholly housed and free from action of the weather; ninth, the provision of novel means for releasing the 90 semaphores, the arrangement being such that when the electromagnet or solenoid which controls the locking of the semaphore is demagnetized said semaphore will be released with absolute certainty no matter what the 95 source of power may be for holding it at "safety;" tenth, the provision of means for protecting the entire system from the effects of statical electricity, whether the same be due to atmospheric conditions or to a statical 100 charge maintained by high pressure from the power-generators or other sources and over the conductors of the system; eleventh, the provision of means for preventing the signaling and switch-controlling batteries of a railway system from freezing; twelfth, the provision of means for preventing the commutators of the operative electric motors of the 105 system from freezing in connection with railway signal apparatus where said apparatus is moved or controlled by such motors; thirteenth, the provision of means for preventing 110

the accumulation of undue moisture in the signal posts or boxes where the signal-controlling mechanism is located; fourteenth, the arrangement of home and distant signals with relation to a train-control or safety appliance carried by a car in such manner that when either signal is displayed it will act as a trip to automatically actuate the train-control or safety appliance if the same be not first manually moved by the motorman or engineer before the car or locomotive reaches said signal; fifteenth, to provide a railway car or train with a train-control or safety appliance for automatically effecting the stoppage thereof, said appliance being adapted to be actuated by a trip located beside the roadway, which trip is adapted to be raised against a constantly-acting force, as gravity, by a source of power and is normally held out of operative relation with the train-control or safety appliance by a source of energy independent of the first-named source of power and with said first-named source of power disconnected from the motive device which lifts the trip, said trip being also adapted to be released either by the failure of the independent source of energy or by the presence of a preceding car or train, the arrangement being such that where a series of such trips are located beside the roadway each trip protects a car or train upon the section controlled by it from a rear-end collision due to a following car; sixteenth, to provide a system of railways with a train-control or safety appliance adapted to automatically disconnect the source of power and apply the brakes to a car or train when acted upon by a trip device beside the roadway, said trip being adapted to be lifted by an applied source of power against a constantly-acting source of power, such as gravity, to a normal position, where it will not act upon the safety appliance, the arrangement being such that when thus lifted the lifting or applied source of power will be disconnected and the trip normally held out of action by a source of energy independent of the lifting or applied source of power, said trip being released either by the failure of the independent source of energy or by the presence of a preceding car or train; seventeenth, to provide an electric-railway system with a train-control or safety appliance adapted to automatically disconnect the power-house generator from the motor or motors on board a car propelled thereby and to simultaneously apply the brakes when acted upon by a trip located beside the roadway, said trip being provided with an electromotive device adapted to be automatically connected to the power-house circuit and to raise the trip device against a constantly-acting force, as gravity, and provided also with additional means controlled by an independent source of energy for normally holding it out of operation with the train-control or safety appli-

ance, the power-house circuit being disconnected from the motive device when the trip is thus held in its normal or inoperative position, the arrangement being such that said trip may be released either by the failure of the independent source of energy or by the presence of a preceding car or train; eighteenth, to provide in a safety system for railways a stop device which is normally held out of operation with a train control or safety appliance carried by a car and against a constantly-acting force, as gravity, with means for certainly effecting its release when the controlling source of energy is disturbed; nineteenth, to inclose the signal-lamps wholly within the signal-box and to provide double or duplex glass or other transparent windows in front of such lamps for admitting of the passage of the rays therethrough at all times without any possibility of the accumulation of moisture thereon, such an arrangement also assuring full protection of the lamps and windows against the acts of malicious persons.

In systems of railway-signals which are controlled by track-circuits through the agency of the wheels and axles of the cars and the track-rails it has heretofore been impossible to utilize relatively high potential batteries or electrical generators directly with the sectional track-circuits, owing to the relatively low resistance between the rails, which resistance varies from time to time by reason of the presence of more or less moisture and the accumulation of iron-dust on the ties due to the friction of the fates and flanges of the wheels upon the rails. In fact, it has been stated in the descriptive catalogues of the prominent railway signal companies of the United States that this resistance often falls to a point as low as three ohms, therefore necessitating the use of signal-controlling batteries in the track-circuits, preferably having an electromotive force of no more than one volt. The use of such low-voltage batteries, therefore, necessitates the use of extremely delicate relays at the signals in the signal-boxes and additional batteries of relatively high voltage, with additional electromagnets for positively controlling the movements of the signals. It is also found to be impracticable to use such systems of delicate relays and low-voltage batteries in connection with electric railways where one of the track-rails is divided into sections and the other bonded together throughout its length so as to constitute the return-circuit of the power-house dynamo and also of the signaling-circuits, for the reason that in the use of enormous quantity currents at relatively high voltages for the propulsion of the cars there is found to be such a drop of potential in the return or track rail part of the circuit that the individual potentials between succeeding sections of the track corresponding to the track-signaling

sections is sufficient to operate or interfere with the working of the track-signal relays, so that various apparatus has heretofore been devised for adapting such systems of signals 5 in connection with electric railways—in one instance the use of polarized relays, thereby further complicating the system.

My present improvement obviates these 10 conditions and enables me to use directly in the track-controlling circuits batteries or electrical generators of any preferred voltage and ampere capacity, the perfection of the insulation obtained by my novel arrangement of track-circuit-controlling rails or conductors 15 making it possible to use relatively high voltage generators and to such an extent as to utilize such batteries for driving the motors which control the signals, thereby eliminating 20 all relays and local circuits.

20 In my prior application above referred to I have claimed, broadly, flexible sectional track-circuit-controlling rails or conductors located closely adjacent to the track-rails and so connected with circuit-controlling batteries 25 and electromagnets as to effect the operation of the signals directly, and also the operation of the switches for sectional third rails where used in connection with an electric railway when a car travels over the route, the flanges 30 of the car-wheels effecting the operation of the controlling-magnets.

One of the essential features of my present improvement consists in effecting a better insulation of these flexible sectional track 35 rails or conductors and in minimizing in so far as possible the frictional wear between the flanges of the car-wheels and such rails.

In the before-mentioned application I have 40 also described, illustrated, and claimed a novel system of semaphore-signal control whereby the semaphores are geared each to the armature of a rotary electric motor having circuit connection with the current feeder or main in multiple branch circuits, shunt- 45 circuits being provided at each signal, which include the coils of a locking-electromagnet for locking the semaphores at "safety" after the motors have been automatically cut out of circuit through the action of the same mag- 50 net, the arrangement being such that diminished current-flow from the feeder is effected through the locking-magnets, while the signals are held at "safety." With such an arrangement, however, there is the objection 55 that should the current-flow be largely diminished, owing to the presence of a number of cars or trains upon any particular portion of the system or for other obvious reasons, which would naturally produce a drop 60 in the current potential, the signals would be released. In my present application I avoid this objectionable feature by providing each signal or semaphore with a local source of electrical energy, preferably a battery, which 65 is wholly independent of or disconnected

from the main source of electrical energy—such, for instance, as the power-house generator when used in connection with an electric-railway system or the main generator, which supplies the current for operating the 70 signal-motors when used in connection with an ordinary steam-railway system. By this arrangement I am enabled to lock the signals always at "safety" no matter what may be the condition of the power-house circuit, the 75 motors of the signals having, preferably, such current-carrying capacity as will enable them to move each signal to "safety," even when there is insufficient current-flow over the feeder to propel a car or train, thereby 80 assuring the absolute operation of the signals under all conditions of usage. In said previous application I have also described and shown the semaphore-arms as adapted to perform the double function of a sema- 85 phone and a trip or train-stop, this for the purpose of simplifying the apparatus, it having been customary heretofore in the use of train-control devices in the nature of trips located beside the track to connect such 90 trips mechanically through a series of levers and links to a semaphore, so that both the semaphore and the trip might be actuated by the same source of power and at the same time, such devices operated by pneumatic 95 pressure and controlled by electricity being well known and in general public use in the art. By thus combining the two in one I am enabled to very materially simplify and cheapen the structural parts. For this reason 100 a number of my claims hereinafter made have been directed to the broad idea of controlling semaphores or signals in the manner hereinafter described, and as illustrated in the drawings, and because of such combined 105 or double function I have also embodied claims hereinafter to the feature of train-control or safety appliances adapted to be actuated by trip mechanism of the character described and shown. That which I 110 have said hereinbefore with relation to the provision of a local source of electrical energy, preferably a battery, which is wholly independent of or disconnected from the main 115 source of electrical energy for locking and controlling the semaphore after the current from the power-house generator has been cut off for raising the semaphores to normal position, applies with equal force with relation to the trip devices, inasmuch as I have, as 120 before stated, combined the semaphores and trip devices in such manner as to constitute a single element adapted to perform a double function.

My invention will be fully understood by 125 referring to the accompanying drawings, in which—

Figure 1 is a diagrammatic view illustrating an electric railway of the sectional third-rail type embodying one form of my im- 130

1
provement, one pair of concealed or housed home and distant semaphores being shown in plan view. Figs. 2 and 3 when placed end to end with Fig. 2 upon the left illustrate my 5 improved system complete with three pairs of home and distant semaphores, their controlling electric motors, together with circuits and circuit connections and one pair of local batteries for each set of semaphores, a 10 power-house dynamo being shown on the right of Fig. 3 and a pair of car-wheels upon the left in Fig. 2, passing from right to left in the direction of the arrows with the home and distant semaphores in the rear displayed, 15 respectively, at "danger" and "caution," other details of improvement being also dia- 20 grammatically illustrated in these figures. Fig. 4 is an enlarged sectional view taken through Fig. 1 on the line V V and as seen looking thereat from left to right in the direction of the arrows, illustrating two forms of sectional track-circuit-controlling rails or conductors and two conduits for inclosing all of the conductors of the system at points approximating the plane of the track-rails. 25 Figs. 5, 6, and 7 illustrate in sectional view three full-sized modified forms of my improved sectional circuit-controlling rails or conductors, together with the conductors 30 of the system, the conduits for inclosing all of the same, a part of a track-tie and one of the track-rails supported thereon, a portion of one of the car-wheels—full size—being shown in dotted lines in Figs. 5 and 7 and full lines in Fig. 6. Fig. 8 illustrates an enlarged sectional view taken through Fig. 2 on the line W W and as seen looking thereat from right to left in the direction of the arrows, showing the track-rails supported by and electrically 40 secured to an iron tie, which in turn is electrically connected to an earth-plate embedded in moist earth, a car being shown in end elevational view upon the track with a safety appliance carried thereby, an iron signal- 45 post of the next signal in advance being also shown in elevational view and electrically secured to the iron tie, the box containing the signal mechanism at the top of the post being shown in sectional view taken on the 50 line Z Z, Fig. 9, and as seen looking thereat from right to left in the direction of the arrows. Fig. 9 is a sectional view taken through Fig. 8 on the line Y Y and as seen looking thereat from left to right in the direction of the arrows, the signal-post, semaphores, and signaling mechanism at the top thereof being shown in elevational view, the signal-lamp and motor for controlling the home semaphore being shown in full lines 60 and the signal-lamp and motor for controlling the distant semaphore in dotted lines, a lightning-rod being also shown in elevational view on top of the signal-box. Fig. 10 is a full-sized sectional view taken through 65 the signal locking, controlling, and releasing

appliances, the controlling-magnet and the appliances for positively and absolutely assuring the releasing of the locking appliances' being shown in side elevational view. Fig. 11 is a sectional view taken through Fig. 10 70 on the broken line X X and as seen looking thereat from the top toward the bottom of the drawings, the novel form of the double or duplex controlling-magnet being shown in plan view. 75

Referring now to the drawings in detail, in all of which like numerals and letters of reference represent like or equivalent parts wherever used throughout the specification, and, first, to Figs. 1, 4, 5, and 6, and particu- 80 larly to Figs. 5 and 6 as to details, 1 1 represent the track-rails, which are effectually bonded together and interconnected, as shown, throughout the entire length of the system, so as to constitute them good elec- 85 trical conductors. 2 2 are sectional third rails of well-known form secured directly to the ties by insulators in the usual way. 3 3 3 3 are sets of flexible track-rails or conductors connected at their centers, respectively, 90 to insulated sectional conductors 4 4 and 11 11. 5 is the insulated current-feeder connected directly to the positive pole of a power-house dynamo or generator 6, the negative pole of which is connected to the 95 track-rails 1 1. 7 7 are third-rail switch and signal controlling magnets connected directly in circuit with batteries 9 9 and the insulated sectional conductors 4 4. 8 8 are switching-armature levers provided with retractile springs which hold them normally on their back-stops, said armature-levers being connected at their pivoted ends directly to the current-feeder 5 and adapted when 100 drawn forward to connect said feeder to the corresponding sectional third rails 2, the back contact being connected in each instance through a conductor 12 and the operative electromotive device of the home signal or semaphore and common return-conductor 110 13 to the track-rails 1 1 substantially in the same manner as disclosed in my before-mentioned application. The additional insulated sectional conductors 11 11 extend in each instance over two entire sections of the road- 115 way, their function being to control the operation of the distant signals or semaphores, and they are connected, respectively, to the central portions of single sets of sectional track-rails or conductors 3 3, parallel with 120 the first-named sets of such rails, as clearly illustrated. 10 10 are additional batteries, their function being to control the operation of the distant signals, said batteries having 125 their positive poles connected directly to the conductors 11 and their negative poles to the track-rails 1. The batteries 9 9 and 10 10 are distinctly local sources of electrical energy for each section—that is to say, they are wholly disconnected from or independent 130

of the power-house generator, so that their action is to absolutely control the locking of the signals at "safety," the function of the power-house generator in so far as it relates to the signals being to lift them to "safety" against the action of a constantly-opposing source of energy, as gravity or a spring, the function of the batteries 9 9 being also to control the switches for the third rails locally, no matter what may be the condition of the power-house circuit.

On inspection of Figs. 1 and 4 it will be noted that the flexible track-rails or conductors 3 3 on the upper side of Fig. 1 and left-hand side of Fig. 4 of the drawings are arranged in pairs and the like sectional flexible track-rails 3 on the other side of the track are arranged in single relation, both sets being of equal length, preferably slightly greater than the length of the shortest car it is designed to run—say about sixty feet. It will also be noted that these several sets of flexible sectional track-rails or conductors are separated at their adjoining ends by definite spaces, preferably equaling the distance between the inner pairs of truck-wheels of each car, the arrangement being such that under no condition will it be possible for a car to pass over the roadway without closing the circuits through the corresponding sectional flexible track-rails at every part of each section on both sides of the track, the car-wheels running free of friction for the intervening spaces. The double arrangement of sectional flexible track-rails 3 3 seen upon the upper side of Fig. 1 and left-hand side of Fig. 4 of the drawings and the manner of supporting the same is illustrated in detail in full-sized sectional view in Fig. 5, in which 14 is a wooden stringer extending over the entire track and preferably painted or treated with insulating material, as liquid asphalt, said stringer being sustained at definite intervals upon the ties—say about every ten feet—by insulating-blocks 15 15 and iron chairs 16, secured by screws to the ties in the manner shown. 17 17, &c., are hard-rubber, vegetable fiber, or equivalent insulating-washers, and 18 18 are bolts extending laterally through the stringer 14, their function being to secure the lower one of the pair of flexible sectional track-rails or conductors 3 3 and to insulate the same in the best possible manner from the wooden stringer, preferably at points about eighteen inches to two feet apart. The upper flexible sectional track-rail of these pairs of rails is in each instance secured by screws directly to a cover 19 for a grooved conduit in the upper surface of the stringer 14, in which conduit are located the current-feeder 5, the pair of insulated sectional conductors 4 4 for the home signals or semaphores, and the additional insulated sectional conductor 11 for the distant signal or semaphore, the cover 19 being hinged at 20,

as shown, and firmly secured at its front edge directly to the stringer 14 by screws 21, extending through metal connectors 22 in such manner as to form the best possible electrical connection between the upper rail 3 and its corresponding inclosed insulated conductor 4. The lower flexible rail 3 is similarly connected, as shown, by an insulated conductor to its corresponding insulated conductor 4 within the conduit.

Referring now to Fig. 6, I will describe in detail the arrangement of the flexible sectional rails or conductors and corresponding conductors illustrated on the right of Fig. 4. The stringers 14 in this instance are made preferably of durable flexible wood—such as hickory, oak, or the like—and are sustained at intervals of about ten feet by yielding steel supporting-arms 23, constructed, as shown, so as to be secured together by bolts 24 directly to the lower flange of the track-rail 1, said parts being effectually insulated therefrom by a sheet of asbestos, vegetable fiber, or other insulating material 25. The yielding arms are also preferably coated with insulating-paint to more effectually insulate them, and their upper or sustained ends are provided with oblong extensions secured by screws in mortises in the lower surface of the stringer 14. In this instance the track-rail or conductor 3 is in the form of an angle-iron secured by screws directly to that surface of the stringer 14 adjacent to the track-rail 1, and it is connected at its center directly by an insulated conductor running to the insulated conductor 11, which in this case is located in an additional conduit 26, secured directly to the ties and provided with a removable cover, as shown, 5 being an additional idle current-feeder for use when desired in the event of the failure of the other feeder above referred to.

In Fig. 7 I have disclosed the preferred form of arrangement of flexible sectional track-rails or conductors for use when it is designed to more effectually insulate said parts, as at points where the track may be flooded. In this instance the wooden stringer 14 is sustained by insulated yielding steel supporting-arms 23, as before, and the conductors 4 4 and current-feeder 5 are located within a conduit 26, insulated from and secured to the ties at intervals and having a flexible wall 27 secured directly to one face of the flexible stringer 14 by screws, as shown, which screws also secure one of the flexible sectional conductors 3, connected, as shown, directly to one of the insulated conductors 4, the other flexible sectional conductor 3 being attached directly to the inner wall of the conduit 26 with its free or upwardly-extending edge located in the path of the movable flexible conductor 3, carried by the stringer 14. The flexible wall 27 is preferably made of steel-wire gauze coated exteriorly and inte-

riorly with rubber or it may be made of alternate layers of rubber and extra strong canvas properly treated in any well-known manner to withstand the action of the weather. This wall is secured at its lower edge to the conduit 26 by a metal strip 31 and screws extending therethrough, said metal strip acting as a support for one of the conductors 4 and the current-feeder 5 and all of said conductors having their insulating-surfaces in metallic connection with each other and with the strip 31, as shown. This strip 31 is in turn electrically connected at intervals to the track-rails 1 for the purpose of effecting the discharge of any statical electricity which may accumulate upon the surface of the conductors of the system. 28 is an angle-iron secured to the upper and inner faces of the stringer 14 and resting normally against the inner face of the track-rail 1, said angle-iron and its supporting-stringer 14 being properly curved or cut away at the ingoing and outgoing ends of each section to readily admit of the wedging action of the flanges of the car-wheels against the face thereof. 25 To the under surface of the cover 19 is secured a metal strip 29, which has a wearing-surface against the upper face of the angle-iron 28. All of the conductors are put in place within the conduit in the manner shown, after which the cover is secured directly to the conduit and through the free edge of the flexible wall 27 by a series of screws 21, extending into the upper side of the conduit 26. Those spaces approximating thirty feet in length between the ends of the flexible sectional rails 3 on both sides of the track are occupied by a continuation of the conduit 26, grooved at its top and having a cover, like 19, in each instance, (see Fig. 8,) and the several conductors are inclosed in this continuation of the conduit, 30 being metal plates, preferably about six inches in width, constituting overlapping end covers for effectually protecting the inner portion of the conduit from the weather, the screws 21 acting at one and the same time to secure all of the parts together.

The operation of this form of the invention will be apparent, it being obvious that when a car enters a section the car-wheels (shown in dotted lines, Fig. 7) will force the angle-iron 28 and stringer 14 to the extreme right or the position shown in dotted lines, 55 so that the flexible rails or conductors 3 are held in good electrical contact with each other at the corresponding parts of each section so long as the flanges of any of the car-wheels are passing between the angle-iron 28 and the head of the track-rail 1, such an arrangement possessing great flexibility.

Referring now to Figs. 8 and 9, I will describe the home and distant semaphores and their relation to the safety appliances carried by the cars. 33 represents an iron tie lo-

cated at the end of each signaling-section and to which the track-rails 1 are secured by brazing material 35 or by welding or in any preferred manner and in such way as to assure the best electrical contact between the rails and the tie. This tie is in turn connected by a conductor to an earth-plate 34, buried in the earth a sufficient distance to assure good electrical contact with moist earth. 32 is a signal-post, preferably of iron, the base of which is brazed, welded, or otherwise secured directly to the iron tie 33, said signal-post having at its top a signal-box, preferably of the conformation shown, for securely housing all of the operative parts of the signaling apparatus, 36 being a protecting housing or hood open at its bottom, which normally effectually incloses both the home and distant semaphores 37 38, said semaphores being connected to operating-motors 39 40 by pinions and gear-wheels 41 42 43, substantially in the manner disclosed in my before-mentioned application and also as illustrated in Figs. 2 and 3. It will be understood that when the semaphores are in safety position they are both housed, the home semaphore 37 being held horizontally and the distant semaphore 38 at an upwardly-inclined angle with their corresponding red and green glass lenses out of the paths of the rays of the lamps 58 58 in the signal-box, (see Fig. 8,) duplex or double transparent openings being provided on the front side of the signal-box for admitting of the passage of the rays and correspondingly free openings in line therewith in the protecting housing or hood 36, (see Fig. 9,) and also that when said semaphores are released the home semaphore 37 hangs vertically and the distant semaphore 38 transverse to the track, (see Fig. 8,) such an arrangement making it impossible for a motorman or engineer to mistake the nature of the semaphore and also placing the end of either semaphore in the path of the operating-arm *a*, connected with the vertically-disposed rod *s*, which in turn is connected to a manually-controlled appliance, as an operating-wheel, the air-brakes and switching mechanism for controlling the movement of the train being of any well-known form, but preferably the same as that disclosed in my before-mentioned application. The signal - box is preferably lined throughout with wood or other insulating material for the purpose of preventing the accumulation of condensed moisture therein, and the glass or other transparent windows in each instance embraces two panes, as shown, separated from each other by a volume of air, said transparent panes of glass being preferably hermetically sealed to the box at their edges, such an arrangement constituting a means for the prevention of the accumulation of moisture or frost in the path of the rays of light from the lamps. This

feature constitutes a very important element of my invention, in that it permits of the absolute inclosure of the lamps 58 within the signal-boxes, thus concealing them from the attacks of malicious persons and placing them in a position in which the temperature is always practically constant, thereby assuring their operation under all conditions of weather and particularly when combined with heating devices hereinafter described. Of course it will be understood that there will be provided at the upper part of the box the necessary outlets for the products of combustion from both lamps and at the bottom of said box the necessary inlets for admitting fresh air through the lower part of the hollow signal-post 32. The housing or hood also effectually protects the journal-bearing connections of the semaphores from the accumulation of ice, thus absolutely preventing any possibility of failure of the movement of the semaphores from this cause. On top of the signal-box I have shown a lightning-rod 60, the function of which is to dissipate any atmospheric electricity which may accumulate in the neighborhood of the semaphore-post, thereby avoiding any damaging action of the same to the mechanism within the box. Of course where the entire signal post and box is of iron this lightning-rod would not be needed, but in the event of the post being of wood a conducting-rod of the kind indicated should be connected with the iron tie 33 or with the track-rails 1, such an arrangement, together with the earthing of the metal strip 31 within the conduit 26 and also the earth connection of the frame of the power-house dynamo 6, as shown in Fig. 3, making it absolutely impossible that any damaging effects from statical electricity can occur either to the system as a whole or to the signaling mechanism in the signal-posts, and this feature constitutes one of the important elements of my invention.

Referring now to Figs. 10 and 11, I will describe a still further and very important novel feature of my invention for assuring the absolute operation of the signaling mechanism and the certain release of the semaphores. These figures of the drawings illustrate in full-sized view an operative appliance, 44 being a locking armature-lever provided with a retractile spring or its equivalent, a retractile weight, and having at its free end a locking-detent with an inclined face, 45 being a controlling-magnet of peculiar form designed to give the best possible electromagnetic results, the same consisting of two spools, as shown in Fig. 11, having each its own core 53 of substantially horseshoe shape, said cores having their opposite ends extending, respectively, into the paths of the ends of two armatures 54 55, the armature 54 being attached directly to the locking armature-lever 44 and the armature 55 to the

free ends of two springs 56, adjustably secured by screws to the trunnion which supports the locking-lever 44. 57 57 are adjustable screws for regulating the tension of the springs 56 and the pressure of the armature 55 against the armature-lever 44, the entire arrangement being such that when the armature 54 is brought into contact with its corresponding poles the second armature 55 will be brought into the field of the other pair of poles and ultimately into mechanical contact therewith, thus completing the magnetic circuit, the usual brass pins, four in number, being provided for preventing sticking of the armatures to the cores. 49 is a locking-drum carried by the same shaft which supports the gear-wheel 43, said drum being provided on one side with a locking aperture or opening 50, adapted to receive the detent end of the locking armature-lever 44. 59 is a metal tongue pivoted in the free end of the locking armature-lever 44 and hanging freely by reason of its own weight, the same constituting means for preventing the locking part of said lever from entering the aperture or opening 50 until the drum 49 shall have rotated the locking-surface of said aperture from right to left a definite distance, so that when the free end of the tongue reaches the wall of the aperture 50 the locking-lever 44 will with absolute certainty be drawn forward under the influence of the magnet 45 and suddenly lock the signal in its concealed position and at the same time break the motor-circuit at a point between the conductors 48 52 and the back contact 51, leaving the signal in locked position, as will be more fully described in connection with the description of the mode of operation of the modified form shown in Figs. 2 and 3 of the drawings, in which the circuit relations of the operative parts of the semaphore-controlling motors 39 40 and the circuit connections between the armature-levers 44 and 47 of the controlling-magnets 45 and 46 and the adjacent circuits between the feeder and the track-rails are not materially different from the operation of the like parts disclosed in the before-mentioned application.

Referring again to Figs. 2 and 3, I will now describe the novel means for preventing the freezing of the batteries 9 and 10 in the signal-boxes and for preventing the freezing of the commutators of the motors 39 and 40 when moisture accumulates thereon, and I will also describe additional means for the prevention of accumulation of undue moisture in the signal-boxes at ordinary temperatures, whereby oftentimes the operation of the electromagnets of such apparatus is materially disturbed. 61, Fig. 3, is a branch conductor running from the positive pole of the battery 9 to and through a switching electromagnet 64 and to metal contacts 63, inclosed in a glass-tube 62, containing mer-

cury, the other end of said conductor being connected to the negative pole of said battery and the arrangement being such that for any temperature above, say, 32° Fahrenheit, 5 or the freezing-point, the armature 65 of the switching electromagnet 64 will be held on its forward contact, the pivoted end of said armature being connected on one side by a conductor 67 to the track-rail, said conductor 10 being included on the other side through a back contact, an electric heater h , and a switch 66 with the current-feeder 5, and the arrangement such that for temperatures below 32° Fahrenheit the mercury will descend 15 in the glass tube 62 a sufficient distance to interrupt the circuit through the switching-magnet 64, thereby allowing the heater-circuit to be closed, so that the temperature within the signal-box will rise owing to the 20 heat generated by the heater h a sufficient amount to prevent freezing of either of the batteries or of the commutators of the controlling-motors. When the temperature rises sufficiently, it will act upon the mercury 25 in the tube 62, again closing the circuit and automatically cutting out the heater. In summer-time or during such seasons as abnormally low temperatures are not reached the switch 66 may be opened, and in like manner 30 the conductor 61 may be disconnected from the switching-magnet 64.

In Fig. 2 I have shown an arrangement whereby the same result may be effected with an open-circuited battery. In this instance 35 the switching-magnet 64 is included in a normally open circuit with the conductor 61 and battery 9 and the mercury in the glass tube 62 supports by flotation a metal weight 68, connected to a vertically-extending stem 40 having mechanical contact with a spring 69, the arrangement being such that when the mercury descends by reason of increased cold the weight 68 will cause the circuit to be closed from the battery 9 through the conductor 61, spring 69, and switching-magnet 45 64, thereby connecting the heater h in circuit with the feeder 5 and track-rails 1. A sufficient rise in temperature due to the heater h will interrupt the circuit and cut it 50 off at the contact-points. I have also disclosed in this figure of the drawings means for preventing the accumulation of undue moisture in signal-boxes, the same consisting of any well-known form of hygrometer 55 70, to the movable or rotary shaft of which or to any of the movable parts of which is connected a conducting-arm 71, having a contact 72, adapted to make electrical contact with mercury in a mercury-cup 73, said parts being 60 included in a normally open circuit with the conductor 61 and the arrangement such that for an abnormal amount of moisture in the box the circuit to the heater h will be closed and remain closed until the amount of heat 65 generated shall dissipate the moisture, when

the hygrometer will automatically cut out the heater. It is obvious that any well-known form of thermostat may be substituted for the mercurial thermostatic devices shown and hereinbefore described for effecting the closure or the breaking of the switching-circuit for the heater h and in such manner as to apply the necessary heat for effecting the result sought. It is also obvious that where the operating-batteries 9 and 10 are located in the base of the signal-posts, as such batteries usually are, two heaters may be utilized in multiple arc in the circuit 67, one for the batteries in the base of the post and the other for the motors and located 75 in the signal-box for maintaining the proper temperature therein.

I will first describe the operation of the modified form of the invention illustrated in Figs. 1 and 4. As shown, both of the switch armature-levers 8 of the two sections illustrated in Fig. 1 are on their backstops, so that current from the power-house dynamo 6 is flowing through the feeder 5 and in multiple-arc relation through all of the switching 80 armature-levers 8 of the system, back contacts, conductors 12, to and through the switch-controlling apparatus for the home semaphores 37, by way of the return-conductors 13 in the signal-posts, to the dynamo, 85 upon the supposition that the controlling apparatus in the signal-boxes for the home semaphores is like that disclosed in my before-mentioned application. The distant semaphores, however, are each operated and 90 controlled in this instance wholly by a battery-current from the local batteries 10, said batteries being in a permanently-closed circuit through the conductors 11 and the track-rails 1, Fig. 1, the operating apparatus and 95 circuit connections in the signal-boxes for the distant semaphores being substantially like that disclosed in Figs. 2 and 3, excepting that the entire movement and control of the distant signals is effected by the batteries 10. 100 In other words, in this modified form of the invention the home semaphores are operated and controlled wholly by the current from the power-house generator through the agency of the local batteries 9 in normally 105 open circuits 4, 4, while the distant semaphores are independently operated and controlled by permanently-closed circuits from the local batteries 10, which are in each instance short-circuited during the time that a 110 car is passing over or standing upon the corresponding sections, such an arrangement constituting absolutely independent control of the home and distant semaphores, so that 115 there is no possibility of a distant semaphore failing to work by reason of the failure of the home semaphore, as is the case with existing well-known types of combined home and distant semaphores, always made dependent upon each other. Suppose then a car to 120

125 130

have entered the section on the extreme right of Fig. 1 and to be passing from left to right. The flanges of the left-hand sets of car-wheels upon entering the same as looking at Fig. 4 will close the circuit between the pair of flexible track-rails or conductors 3 3 and the insulated sectional conductors 4 4 from the battery 9 (see Fig. 1) through the switching-electromagnets 7, thereby causing the switching armature-lever 8 to be drawn to its forward contact, interrupting the semaphore-controlling circuit through the conductor 12 to the home signal 37 and allowing said semaphore to drop by its own weight to "danger," at the same time establishing a working current through the sectional third rail 2 and to the motors on board the car. The flanges of the right-hand sets of car-wheels on passing between the right-hand track-rail (see Fig. 4) and flexible track-rails or conductors 3, supported by the stringer 14, will make good metallic contact between said flexible rail or conductor and the track-rail 1, thereby short-circuiting the battery 10 at the outgoing end of the section which the car has just entered. Consequently no current will flow through the conductor 11 to the rear and to the signal operating and controlling mechanism for the distant semaphore at the end of the section on the left of Fig. 1, as will be apparent if the corresponding circuits be examined in Figs. 2 and 3 of the drawings. Hence the distant semaphore at that point will be released and drop by action of gravity to its exposed position. As the flexible sectional track-rails 3 3 on both sides of the track are of slightly greater length than the shortest car it is designed to run, and as the distance between the successive pairs of said track-rails is slightly less than the distance between the pairs of truck-wheels at the opposite ends of the car, the circuit relations just described will never be disturbed as a car or train passes from one set of such rails or conductors to another, and as the proportions of such track-rails and the absence thereof are approximately equal the friction of the flanges of the car-wheels will be minimized and the amount of metal required for such track-rails will in like manner be minimized, thereby increasing the total insulating effect and minimizing the total frictional effect.

For the purpose of further insuring effective insulation of the track-circuit-closing rails or conductors, and particularly at places in the roadway where there is danger of flooding by water, the modified form illustrated in Fig. 7 is especially designed, and the operation of this form of circuit-closing appliances will now be described. The metal angle-iron 28, supported upon the upper surface of the stringer 14, in this instance constitutes simply a wearing-surface and rests normally with its free lateral face against the lateral head of the track-rail 1, the stringer 14, as

before stated, being made preferably of hickory, oak, or other wood of great durability and sustained, as stated, by yielding steel supporting-arms secured directly to the bottom flange of the track-rail. When the flange of the car-wheel, as shown in dotted lines, enters between the angle-iron 28 and the head of the rail 1, the stringer 14 is forced away and into the position shown in dotted lines, carrying with it that one of the flexible track-rails or conductors 3 which is secured thereto, ultimately bringing it into firm electrical contact with its companion flexible rail or conductor 3, secured directly to the inner face of the conduit 26, the yielding wall 27 assuming the position shown in dotted lines. With such a structural arrangement the insulation of all of the contacts and conducting parts of the system is absolutely assured, it being understood that the space between the successive pairs of stringers 14 is replaced by sections of a covered conduit to which the ends of the flexible wall 27 is effectively secured in such manner as to make the entire conduit waterproof, the metal strips 31 being situated only in those sections wherein the flexible sectional conductors 3 3 are located.

Referring now to Figs. 2, 3, 8, and 11, Fig. 2 having previously been placed on the left of Fig. 3, I will describe the mode of operation of the preferred form of apparatus and all of the details of construction which render the releasing of the signals or semaphores of my improved system practically certain of operation in all conditions of weather. It is to be noted, however, before proceeding, that in Figs. 2 and 3 of the drawings for simplification I have shown the flexible sectional track-rails 3 3 upon opposite sides of the track as continuous throughout each section, and it may be assumed, for the purpose of simplifying the description, that the modified form of flexible sectional track-rails utilized in this form of the invention is that disclosed in Fig. 6 of the drawings, in which the current from both batteries passes through the flanges of the wheels, the yielding-supported rails, and the track-rails. In these figures of the drawings, *w w* represent rear wheels of a car which has just entered the section to the extreme left of Fig. 2 and is passing from right to left, as shown by the arrows in the road-bed. Consequently the battery 9 at the outgoing end of the same section (but not seen) is short-circuited through the flanges of the upper wheels, so that both of the controlling-magnets 45 and 46 for the home semaphore 37 are demagnetized. When this occurred, (referring to Figs. 10 and 11,) the locking-drum 49 was released the instant the armature 54 of the locking armature-lever 44 was demagnetized, or if for any reason it should have stuck or been held in its forward or locked position when the magnet was demag-

netized the armature 55 when released would have by reason of the action of the strong springs 56 struck the armature-lever 44 a sudden blow, thereby assuring the release of the inclined locking-detent at the upper end of the armature-lever 44. When this armature-lever 44 reaches its back contact-stop, the motor-circuit for the controlling-motor 39 is fully closed at the point 51 through conductors 48 and 52, but it will be noted that the same circuit was broken at the front contact of the armature-lever 47 when the magnet 46 was demagnetized. Hence the motor being out of circuit the home semaphore 37 falls by reason of its own weight to the vertical position indicated in dotted lines in Fig. 8, the gearing between the gear-wheel 42, pinion 41, and gear-wheel 43, and the inertia of the armature acting as a brake against the too sudden movement of the semaphore. In like manner the battery 10 at the outgoing end of the section upon which the wheels *w w* are standing was short-circuited by the lower wheel *w* in the same manner as was the battery 9 by the other wheel, so that the armatures 44 and 47 of the controlling-magnets 45 and 46 of the distant semaphore 38 at the right-hand side of Fig. 2 of the drawings were released and the action with relation to the operative parts of that semaphore was identically the same as that attributable to like parts of the home semaphore 37 just described, as will be readily understood upon tracing the circuits, said distant semaphore dropping by its own weight, as did the home semaphore, to the position shown in full lines in Fig. 2 and in dotted lines in Fig. 8. Should any car therefore enter the section on Fig. 2 between the semaphores just displayed, the home semaphore 37 at the right of that figure will drop by its own weight to vertical position, thus displaying both the home and distant semaphores on the right of Fig. 2 in the positions indicated in dotted lines in Fig. 8, at the same time displaying the distant semaphore in Fig. 3 at "caution," thus giving to an incoming motorman or engineer upon the section between Figs. 2 and 3 a double warning indicative of the fact that there are two cars or trains upon the sections immediately in advance.

When a car leaves any section, the circuit controlling and operating appliances for the semaphores resume their normal relations and the motor-circuits are closed for the corresponding home and distant semaphores through the armature-levers 47 44 and back contacts 51, so that the armatures of the corresponding motors 39 and 40 are set in operation and the semaphores rotated to their safety positions until the toes of the corresponding tongues 59 are released on passing the inclined edge of the aperture or opening 50 in the locking-drum 49, (see Fig. 10,) 55 these tongues having in each instance a move-

ment through an angle of less than one hundred and eighty degrees and being so related to the armature-lever 44 and the surface of the drum 49 that they always admit of the certain locking and unlocking of the parts, 70 and particularly when combined with the additional special type of controlling-electromagnet 45, with its armatures 54 and 55, as hereinbefore described. Should the motorman or engineer fail to observe the display of 75 either the distant or the home semaphores, the arm *a* of the train-control or safety appliance on board the car *c* will be rotated when it comes into contact with the end thereof, thus acting as a trip device to cut off the steam or 80 other source of power and simultaneously applying the brakes, as will be obvious on inspection of Fig. 8, where the exposed positions of both semaphores or trips is made clear in dotted lines. It will also be apparent that should any car move backward out of the end of the section upon which it is for the time being standing the corresponding home and distant semaphores or trip devices for the next section in the rear will be displayed, and also should any train be severed and a part thereof left upon any part of the track the corresponding home and distant semaphores or trip devices will be displayed 85 so long as any car remains upon the track at 90 that point. Although I prefer to use two batteries 9 and 10 for each pair of signals, obviously one battery might serve the same purpose, said battery being connected in each instance in multiple to the conductors in the 95 manner shown in dotted lines in Figs. 2 and 3. I prefer to utilize two batteries, as is ordinarily done in signal systems of this nature, and to provide the usual switches, circuits, and circuit connections whereby the batteries 100 may be connected in any preferred relation, and where storage batteries are used one battery may be utilized while the other is being charged, such matters coming well within the skill of those versed in the art. 110

I do not limit my invention to the especial details of construction illustrated in the accompanying drawings, as a number of the features thereof might be materially departed from and still come within the scope 115 of my claims hereinafter made. To illustrate, the armature-levers 65 of the switching-magnets 64 for the heater *h* might be permanently held on their forward contacts and the heaters connected in circuit manually by the 120 switches 66 by a track-walker or other authorized employee at such times as the atmospheric conditions of the weather might justify, variable resistance means being provided in a manner well understood for regulating the amount of current which the heater 125 should utilize under such conditions; nor do I limit myself to the use of electrical heaters, as obviously the same might be replaced by any well-known source of energy for 130

generating heat, combined with means for automatically effecting the generation of such heat when the temperature or hygroscopic conditions of the weather justify the use thereof, as I believe it is broadly new with me to provide means for automatically preventing freezing of the batteries and the commutators of rotary motors in connection with systems of electrical energy generally where there is danger of damaging effects due to such freezing, and my claims are generic as to these features. I believe it is also broadly new with me to devise a signaling system for railways embodying home and distant signals in which the companion pairs of signals are operated and controlled absolutely independently of each other, thereby avoiding any possibility of accident due to such interconnected operations as have heretofore been found necessary in connection with signals of this type. I believe it is also broadly new with me to place the operative conductors of a signaling system for railways in close proximity to the track-rails and to connect the entire system with the earth at different points in such manner as to effectually overcome the damaging effects of statical electricity, whether the same be due to the action of the generators used in connection with the system or to atmospheric electricity, and my claims are also generic as to this feature. I believe it is also broadly new with me to so arrange the home and distant signals of a railway system in connection with a safety appliance or appliances carried by a car that the exposure of either of said signals as a warning to a motorman or an engineer will automatically stop his train or car unless he manually slows down his train before he reaches the corresponding signal. I believe it is also broadly new with me to house both the home and distant signals when at safety position and to so arrange them that when either is displayed the angular position as viewed from the motorman's or engineer's cab is such as to avoid any possibility of his mistaking the nature thereof and that it is new with me to completely house the signal-lamps and to combine therewith duplex transparent windows inclosing hermetically-sealed volumes of air in such manner as to prevent the presence of moisture or frost in the paths of the rays of the lamps. I believe it is also broadly new with me to provide means for assuring the absolute release of a semaphore or signal when locked or held against the action of gravity by imparting a preliminary blow to the locking or retaining part of the mechanism, no matter what may be the nature of the signal or what the means for holding the same. It is also obvious that the novel feature of duplex transparent windows or glasses in signal-boxes makes it possible to utilize the signal-lamps in day-time as well as at night for the purpose of generating

sufficient heat to prevent the freezing of the batteries and commutators of the motors when both are located in the signal-boxes, so that this single source of heat and light in each box is rendered capable of serving a double function, such an arrangement also making it possible to more effectually insulate such signal-boxes from extreme cold and from the condensation of moisture in the interior thereof.

In place of the oil-lamps 58 58 shown in the drawings I may substitute electric lamps having sufficient current-carrying capacity adapted to generate sufficient heat for the purpose of keeping the signal-box warm enough to prevent the batteries and commutator-brushes of the motor from freezing, such lamps being included in circuit in place of the heater and adapted to be inserted in the circuit by a hand-switch.

I am aware that it has heretofore been proposed to operate or control electric railway signals by utilizing one of the track-rails and a flexible supplemental conducting-rail closely adjacent thereto in connection with a signal battery and an electric circuit connected to the track-rail and such flexible rail, as disclosed in British Patent No. 2,169 of 1889 and in United States patent to Means, No. 273,377; also, that it has heretofore been proposed to operate or control electric railway-signals by utilizing both of the track-rails and a pair of rigid supplemental conducting-rails yielding supported at their ends and connected together electrically and to one or more electrical circuits including one or more signals, as disclosed in United States patent to Thaler, No. 491,387. In all of the before-mentioned patents, however, it is proposed to utilize the tread-surfaces of the car-wheels for effecting electrical connection between the track rail or rails and the supplemental rail or rails. While such an arrangement would be operative, it is open to the objection that with many existing types of rails the head of the rail is practically the same width as the tread-surface of the car-wheels, so that oftentimes such an arrangement would be impractical, and I make no claim hereinafter to this feature *per se*, my claims in this particular being limited specifically to the utilization of the flanges of the wheels between the track-rail and the supplemental conducting-rail and the yielding support of such rails in such manner as to effect the desired result. I am also aware that railway-signals have heretofore been devised, as disclosed in United States patent to E. A. Sharp, No. 385,963, July 10, 1888, in which all of the operating and controlling parts thereof are inclosed within a signal-box having one transparent window on each side of a lateral extension thereof and a lamp having a single transparent window secured to said lateral extension exterior to the box and in

such manner that the three transparent windows permit of the passage of rays of light from the lamp through all of them and a transparent signal-disk, and I make no 5 claim hereinafter broad enough to include such a structural arrangement, my most generic claim in this particular being directed to a signal-box which wholly incloses the operating and controlling mechanism, said signal-box being provided with double or duplex transparent windows and a lamp also wholly inclosed within the box and in such manner that the lamp not only constitutes a means for transmitting light through the 15 transparent windows, but also constitutes an agency of heat sufficient to maintain the entire signal-box heated to such an extent as to overcome the deleterious effects of cold upon the operating and controlling mechanism 20 and also upon the oil of the lamp itself, as well as to effect a complete protection of the lamp against the attacks of vandals.

Having thus described my invention, what I claim, and desire to secure by Letters Patent of the United States, is—

1. In a railway system a track-circuit-controlling conductor located closely adjacent to but out of contact with one of the track-rails and an electrical circuit including a signal device and a source of electrical energy, said conductor being provided with supporting means which will permit it to yield laterally when the flange of a car-wheel enters between it and the adjacent rail, substantially 35 as described.

2. A railway system provided with a series of insulated conductors and a series of track-circuit-controlling conductors electrically connected thereto and in close proximity to 40 the track-rails, said track-circuit-controlling conductors approximating the length of the shortest car or train it is designed to run and separated from each other by definite spaces approximating also the length of such car or 45 train; in combination with electromagnets and a source or sources of electrical energy in circuit with said insulated conductors, substantially as described.

3. A railway system provided with insulated conductors, an electromagnet and a source of electrical energy in circuit therewith; in combination with a series of sectional track-circuit-controlling rails or conductors electrically connected to said insulated conductors at intervals and separated from each other by definite spaces, said track-circuit-controlling rails being located closely adjacent to and insulated from the track-rails so as to be acted upon by the wheels of 55 cars as they pass over the route, substantially 60 as described.

4. A railway system provided with a track-circuit-controlling rail or conductor yieldingly supported against lateral movement at intervals in close proximity to the track-rails and

insulated therefrom, substantially as described.

5. A railway system provided with track-circuit-controlling rails or conductors sustained by insulating-stringers and yielding 70 supporting-arms connected to the stringers at intervals, said track-circuit-controlling rails being located closely adjacent to the track-rails and insulated therefrom, substantially as described.

6. A railway system provided with a track-circuit-controlling rail or conductor sustained at intervals by insulated yielding supporting-arms secured directly to the track-rail, the arrangement being such that said circuit-controlling rail or conductor is adapted to move laterally when the flange of a car-wheel passes between it and the track-rail, substantially as described.

7. A railway system provided with home 85 and distant signals arranged in pairs; in combination with electric circuits and circuit connections for operating and controlling said signals, each distant signal being absolutely independent of its companion home signal in 90 its mode of operation and control, substantially as described.

8. A railway system provided with a series of home and distant signals arranged in pairs, each home signal being provided with track-circuit-controlling devices, electromotive devices, circuits and circuit connections whereby one set of car-wheels effects its operation and control; the companion distant signal being similarly provided with track-circuit- 95 controlling devices, electromotive devices, circuits and circuit connections whereby the other set of car-wheels effects its operation and control, the arrangement being such that said signals are wholly independent of each 100 other in their operation, substantially as described.

9. A railway system provided with sectional track-circuit-closing-rails or conductors closely adjacent to each track-rail and a 110 series of home and distant signals arranged in pairs; together with sources of electrical energy, circuits and circuit connections between one set of sectional track-circuit-closing rails or conductors and the home signals 115 and similar sources of electrical energy, circuits and circuit connections between the other sectional track-circuit-closing rails or conductors and the distant signals, whereby each signal is made independently operative 120 when a car is standing upon or passing over the section, substantially as described.

10. A railway system provided with track-circuit-controlling rails or conductors yieldingly supported at intervals and separated 125 from each other by intervals approximating the lengths of said rails; together with electromagnets and local sources of electrical energy included in circuit therewith, said track-circuit-controlling rails being located in close 130

proximity to the track-rails and effectually insulated therefrom, substantially as described.

11. A railway system provided with track-circuit-controlling rails or conductors located in an insulating-conduit and yieldingly supported in close proximity to the track-rails, substantially as described.

12. A railway system provided with a series of pairs of track-circuit-controlling rails or conductors located in an insulating conduit and connected each to an insulated conductor located also in said conduit and including in circuit a source of electrical energy and an electromagnet, said circuit-closing rails or conductors being separated at intervals by spaces approximating their lengths and the insulated conductors inclosed in intermediate continuations of the conduit, substantially as described.

13. A railway system provided with insulated electrical conductors located in a conduit closely adjacent to the track-rails and connected to an electromagnet and a source of electrical energy; in combination with pairs of sectional track-circuit-controlling rails or conductors included in the same conduit and connected through a flexible wall with a yieldingly-supported stringer closely adjacent to one of the track-rails; together with means operatively controlled by the before-mentioned electromagnet substantially as described.

14. A railway system provided with a power-house dynamo, an insulated current-feeder connected to one pole thereof, the other pole being connected to one or both of the track-rails; in combination with a series of sectional third rails; a series of sectional track-circuit-controlling rails or conductors adapted to be actuated by the wheels of the cars and electrically connected to a corresponding series of insulated conductors each including in circuit a local source of electrical energy and a switching-electromagnet; the current-feeder and the insulated conductors being inclosed in a conduit located in close proximity to the track-rails, substantially as described.

15. In a railway signal system a line of track-rails and a circuit-controlling rail or conductor closely adjacent to each track-rail; in combination with independent signals and electrical circuit connections so arranged that the car-wheels on one side of a car or train actuate one signal and those upon the other side thereof, the other signal, substantially as described.

16. Home and distant semaphores provided with means for holding the former in a position transverse to the track and the latter at an angle thereto, and so arranged that when both are set, the one for danger and the other for caution, the first-named semaphore will hang vertically and the other transverse

thereto with their exposed ends adjacent to each other or overlapping, substantially as described.

17. Home and distant semaphores pivotally supported and provided with means for adapting them, when displayed respectively at danger and caution, to appear in view one in a vertical and the other in a transverse position, substantially as described.

18. Home and distant semaphores pivotally supported and normally concealed in a housing, said semaphores being provided each with means for locking it against a constantly-acting force, as gravity, the home semaphore when released being adapted to hang vertically and the distant semaphore when released to hang transversely, whereby an unmistakable individual indication of the nature of the semaphore is had, substantially as described.

19. A semaphore adapted to be held in a definite position against a constantly-acting force by means electromagnetically controlled; in combination with additional means also electromagnetically controlled in the same direction as the first-named means and controlled in its movement in a reverse direction by an independent force, said additional means being for the purpose of assuring the release of the semaphore when the controlling-current is interrupted, substantially as described.

20. A semaphore provided with electromagnetically-controlled means for locking it in a definite position against a constantly-acting force; in combination with additional means also electromagnetically controlled in the same direction as the first-named means and in a reverse direction by an independent force for the purpose of imparting to the locking means a releasing blow when the current-flow is interrupted to the controlling-electromagnet, substantially as described.

21. A semaphore adapted to be held in a definite position against the force of gravity by electromagnetically-controlled means and additional means controlled by the same magnet for assuring the release of the semaphore when the controlling-current is interrupted, substantially as described.

22. A semaphore operatively connected to a motive device for raising it to a definite position against the force of gravity; in combination with electromagnetically-controlled means for maintaining said semaphore in its raised position; together with additional means electromagnetically controlled in the same direction as the first-named means and in a reverse direction by an independent force for assuring the release of the semaphore when the controlling-current is interrupted, substantially as described.

23. A semaphore supported by a rotary shaft operatively connected to the armature of an electric motor; in combination with

electromagnetically-controlled locking means for holding said semaphore in a definite position against the force of gravity; together with additional means for assuring the release 5 of the locking means when the controlling-current is interrupted, said additional means being electromagnetically controlled in the same direction as the locking means and in a reverse direction by an independent source 10 of energy, substantially as described.

24. A semaphore operatively connected with a motive device for rotating it to a definite position against the force of gravity; in combination with an electromagnet having a 15 locking armature-lever provided with a locking-detent and means for preventing the locking action of the detent until the part to be locked has been moved or rotated a definite distance past its final or ultimate locked position, substantially as described.

25. A semaphore operatively connected to the armature of an electric motor; in combination with an electromagnetic locking device having an armature-lever provided with 20 a detent for locking the semaphore in a definite position against the action of a constantly-acting force, as gravity; together with means for preventing such locking action until the part to be locked has been 25 moved or rotated past its final or locked position, and a circuit-interrupting device carried or operated by the locking armature-lever, the arrangement being such that when the locking action is finally effected the motor-circuit is broken, substantially as described.

26. A railway system embracing track-rails bonded or interconnected together throughout the entire system and electrically 30 connected to earth; in combination with a series of insulated conductors having their insulated surfaces also electrically connected to earth, whereby the system is protected from the evil effects of statical electricity, 35 substantially as described.

27. A railway system embracing track-rails bonded together throughout the entire system and connected to one pole of a power-house generator; in combination with insulated conductors embracing the current-feeder and signaling-circuits having their insulated surfaces electrically connected to earth, the track-rails also being connected to earth, whereby the system is protected from 45 the evil effects of statical electricity, substantially as described.

28. A railway system embracing track-rails electrically connected together throughout the entire system and to earth; a power-house dynamo or generator having one pole connected to the track-rails and its frame connected also to earth; an insulated current-feeder connected to the other pole of the power-house generator and a series of insulated 55 signaling-circuits operatively connect-

ed to signals, the insulated surfaces of all of said conductors being connected to earth, whereby the system is protected from the evil effects of statical electricity, substantially as described.

29. A railway system embracing track-rails electrically connected together and to earth; a series of signals supported by signal-posts also electrically connected to earth; and a series of insulated signaling-circuits located substantially in the plane of the track-rails, the insulated surfaces of the conductors being also electrically connected to earth, whereby the entire system is protected from the evil effects of statical electricity, 70 substantially as described.

30. A railway system embracing a pair of track-rails electrically connected together throughout the system and electrically connected with metal ties at definite distances 75 corresponding to the lengths of the signaling-circuits, said ties being connected electrically to earth; in combination with signal-posts electrically connected to the metal ties; together with insulated signaling-circuits located substantially in the same place as the track-rails, whereby the entire system is effectually protected from the evil effects of statical electricity, substantially as described.

31. A railway system embracing a pair of track-rails electrically connected together and to earth; in combination with a series of insulated signaling-conductors located closely adjacent to the track-rails; together with a series of signals included in circuit therewith 80 and supported at visible points above the level of the track, the supports for said signals being also electrically connected to earth, whereby the entire system is effectually protected from the evil effects of atmospheric 85 electricity, substantially as described.

32. In a railway system one or more semaphores provided with an electric motor or motors for controlling the movement thereof; in combination with one or more local batteries and heating means for preventing the batteries and the commutators of the motors from freezing; together with automatically-controlled means for effecting the operation of said heating means when the temperature 90 approximates freezing-point, substantially as described.

33. A railway-signal operatively connected with the armature of an electric motor; in combination with heating means and automatically-controlled means for effecting the operation of said heating means when the temperature approximates freezing-point, whereby the commutators are prevented from 95 freezing, substantially as described.

34. A railway-signal having inclosed operating mechanism and heating means for dissipating condensed moisture upon the operative or controlling parts; in combination with means controlled by the presence of 100

moisture within the inclosure for automatically effecting the operation of said heating means, substantially as described.

35. A railway-signal embracing a signal-box provided with double transparent windows inclosing a volume of air between them; in combination with a rotary electric motor having its armature operatively connected to the signal and a lamp all wholly inclosed with-
10 in the box, substantially as described.

36. A railway-signal embracing a signal-box provided with double transparent windows inclosing a volume of air between them; a lamp and a rotary electric motor having its
15 armature operatively connected to the signal and also inclosed within said box; said signal being located wholly without the box, whereby condensed moisture upon the windows is prevented and the freezing of the commuta-
20 tors of the motor avoided, substantially as described.

37. A railway-signal embracing a signal-box provided with double transparent windows separated from each other by a transpa-
25 rent medium which is a relatively poor con-
ductor of heat; in combination with a lamp and a source of electrical energy, as a battery, adapted to be effected by the heat generated by the lamp, substantially as described.

38. A railway-signal embracing a sema-
phore, a signal-box inclosing a rotary electric motor having its armature operatively connected to said semaphore; in combination with a lamp also inclosed in said box, the lat-
35 ter being provided with double transparent windows separated from each other by a trans-
parent medium and all so arranged that both the heat and the light of the lamp are utilized, substantially as described.

40. 39. A railway-signal embracing a sema-
phore provided with a colored lens, inclosed operating mechanism, and a lamp also wholly inclosed; in combination with double trans-
parent windows separated from each other by a transparent medium which is a rela-
45 tively poor conductor of heat, said windows being in alinement with the light-giving por-
tion of the lamp and the colored lens when the semaphore is in its abnormal position,
50 substantially as described.

40. A railway-signal embracing a sema-
phore operatively connected with mechanism wholly inclosed in a signal-box; in combi-
55 nation with double transparent windows for the box separated from each other by a transparent medium which is a relatively poor conductor of heat, and a source of light and heat also inclosed in said signal-box, whereby the operative parts of the mech-
60 ism are protected from the evil effects of moisture and cold and the light-rays are never interfered with by frost or ice, sub-
stantially as described.

41. In a railway system a home and a dis-

tant semaphore pivotally supported and 65 adapted when released, the one to hang vertically and the other transversely with their free ends overlapping; in combination with a car provided with a safety appliance having an operating-arm the free end of which ex-
70 tends into the path of the end of either of said semaphores when released, substantially as described.

42. A railway-signal embracing a signal-lamp, a signal-box which wholly incloses said lamp, said box having a transparent window for permitting the passage of rays of light therethrough from the lamp, and means for preventing the condensation of moisture upon said window, substantially as described. 75

43. A railway-signal embracing a signal-arm carrying a colored lens or glass; means for rotating said arm; in combination with a signal-lamp, the rotating means and the lamp being wholly inclosed within a signal-box 85 provided with a double transparent window for preventing the condensation of moisture, substantially as described.

44. In a railway system a current-feeder extending over the route and operatively 90 connected to a power-house generator; a series of signals provided each with a rotary electric motor and means for connecting it to said current-feeder and disconnecting it from the same; in combination with release 95 mechanism for the signals embracing controlling-electromagnets included in a local circuits operatively controlled by a car or vehicle as it passes over the route, substan-
100 tially as described.

45. In a railway system a series of home and distant signals and automatic-stop mechanism carried by a car or vehicle, said stop mechanism being connected to a source of power which drives the car and adapted to 105 be automatically actuated when either a home or a distant signal is released, substan-
tially as described.

46. In a railway system a power-house generator operatively connected to a current-
feeder extending over the route; a single series of sectional third rails or conductors and electromagnetic switching devices one only for each sectional third rail or conductor for connecting the same to and disconnecting 110 them from the current feeder or main; a series of electrically-controlled signals, one for each sectional third rail or conductor, and circuits and circuit-controlling contacts so arranged with relation to the armatures of 115 the electromagnetic switching devices, the sectional third rails and the signals, that when any one of said armatures is in one position the current-feeder is connected to the corresponding sectional third rail or conductor and the signal displayed at danger, and when in a reverse position the signal is dis-
120 played at safety and the sectional third rail 125

disconnected from the feeder, substantially as described.

47. In a railway system a main source of electrical energy, as a dynamo-electric machine; a current-feeder extending therefrom over the route or a portion thereof; a series of signals, such as semaphores, operatively connected each with an electric motor for moving it in one direction, and a constant opposing source of energy for moving it in a reverse direction; in combination with a local source of electrical energy for each signal wholly independent of or disconnected from the main source of electrical energy and including in its circuit a controlling-electromagnet for the signal; together with branch circuits from the current-feeder to the motors and circuit-interrupting devices therefor, the arrangement being such that all of the motors are normally disconnected from the feeder and the signals held at safety, each by its own control-magnet, the presence of a car on any section releasing the corresponding signal and allowing the constant force to set it at danger, substantially as described.

48. In an electric-railway system a power-house generator; a current-feeder extending therefrom over the route or a portion thereof; a series of sectional third rails or conductors for conveying current to the motors on the cars; a series of switching-electromagnets, one for each sectional conductor and a local source of electrical energy for each switching-magnet; a series of signals, one for each section, and an electric motor for each signal; a series of branch circuits from the feeder to the corresponding switches controlled by the switching-electromagnets, said switches having connection when in one position with the signal-motors and when in a reverse position with the corresponding sectional third rails, each signal being provided with a local source of energy which opposes the action of its motor, a circuit-interrupting device and a control-magnet; all so arranged that the main source of electrical energy is utilized for propelling the cars and for setting the signals to safety, and the local sources of electrical energy used for moving the switches and controlling the signals, whereby fluctuations in the working current cannot effect the operation of the signals when set to safety, substantially as described.

49. In a railway system a main source of current-supply; a series of signals operatively connected each with an electric motor having a multiple branch circuit connection with said source of current-supply; in combination with a local source of current-supply for each signal and a control-magnet in circuit therewith; together with circuit-interrupting devices for the main circuit, and circuits and circuit connections whereby normally all of the signals are set in a definite position with

their motors out of circuit and each signal held by its control-magnet against a constantly-acting force, substantially as described.

50. In a railway system an automatic train-control or safety appliance carried by a car and adapted to disconnect the propelling-motor from the source of power which propels said car; in combination with a stop device or trip actuated in one direction by an applied source of power and in a reverse direction by a constantly-acting source of energy; together with an independent source of energy for holding said stop device normally out of action with the train-control device and against the constantly-acting source of energy, the first-named applied source being normally disconnected from the stop device or trip, substantially as described.

51. A train-control or safety appliance carried by a car or train for effecting the automatic stoppage thereof; in combination with a stop device or trip for actuating said appliance, said stop device being actuated in one direction by an applied source of power and in a reverse direction by gravity; together with locking or holding means therefor controlled by an independent source of energy and all so arranged that the applied source of power is disconnected from the stop device when it is set in its normal or inoperative position with relation to the train-control or safety appliances of all cars or trains, substantially as described.

52. In a safety system of railways a train-control or safety appliance; a stop device or trip therefor adapted to be moved in one direction by a source of power and in a reverse direction by gravity; in combination with means controlled by an additional source of power for disconnecting the first-named source of power from the stop device or trip and for normally holding the trip out of action with the train-control appliance; together with means controlled by a car for releasing the stop or trip so that it will fall by the action of gravity, substantially as described.

53. In a safety system of railways a train-control or safety appliance; a stop device or trip provided with electromagnetic means for holding it out of the path of said safety appliance and adapted to fall by the force of gravity into the path thereof, when released; in combination with means electromagnetically controlled for positively assuring said release, substantially as described.

54. An electromagnetically-controlled stop device or trip for actuating a safety appliance carried by a car, said stop device being normally magnetically held out of action with the safety appliance and against the force of gravity and provided with means controlled by the holding means for impart-

ing a releasing-blow to said holding means when demagnetized, substantially as described.

55. A stop device or trip for actuating a train-control device embracing electromagnetic means which normally holds it out of operation with the train-control device; in combination with magnetically-controlled means for surely releasing the stop device

when the controlling-magnet therefor is de- 10 magnetized, substantially as described.

In testimony whereof I have signed my name to this specification in the presence of two subscribing witnesses.

CHARLES J. KINTNER.
